UNITED STATES PATENT OFFICE.

HENRY F. KELLNER, OF SILVER LAKE, KANSAS.

SILT-ACCUMULATING MEANS FOR WATER-CURRENTS.

1,355,052.

Specification of Letters Patent.

Patented Oct. 5, 1920.

Application filed July 14, 1920. Serial No. 396,308.

To all whom it may concern:

Be it known that I, HENRY F. KELLNER, a citizen of the United States, residing at Silver Lake, in the county of Shawnee and 5 State of Kansas, have invented certain new and useful Improvements in Silt-Accumulating Means for Water-Currents, of which the following is a specification.

This invention relates to an improvement 10 in means for deflecting water currents of silt bearing streams to form silt-beds, useful to prevent washing of the banks, and to be employed in forming land areas in the beds of rivers or harbors where silt is carried by 15 tide waters.

The object of the invention is to provide 20 fascines which may be conveniently constructed and will operate to great advantage in deflecting water currents for the purposes mentioned.

In the accompanying drawing, Figure 1 is a perspective view of one of the fascines. Fig. 2 is a view of the same in side elevation. Fig. 3 is a view of connected fascines arranged for the protection of the bank of a stream. Fig. 4 is a view of connected fascines arranged transversely of a water current to form silt accumulations in the bed of a stream.

25 Referring now to the drawing, the herein described silt accumulating means consist of a plurality of fascines 2 disposed end-to-end and connected by cables or strands 3, and secured to the bank or shore by a cable or pair of cables 4, the fascines being similar with respect to each other and of such construction that they will deflect moving water to advantage.

Each fascine is made by use of a pair of 30 sections 5 and 6, and cross-strips 7. Section 5 consists of a pair of parallel, adjacently-disposed strips 8 and a pair of parallel, adjacently-disposed strips 9 disposed at right angles to the strips 8 and connected there- 35 with by any suitable means at their intersecting parts, the means herein shown being thongs 10. Section 6 consists of a pair of parallel, adjacently-disposed strips 11 and a pair of parallel, adjacently-disposed strips 12 disposed at right-angles to the strips 11 and having their intersecting parts connected by thongs 13.

The cross-strips 7 are disposed approxi- 40 mately parallel in engagement with the strips of sections 5 and 6 at the intersecting

parts of the strips of said sections, and are secured thereto by the thongs 10 and 13.

The strips 7, 8 and 9 mentioned are preferably of uniform length, and since the strips project outwardly at uniform distances from a thong 10 or 13, the area, in plan and side elevation of a fascine will be approximately equal. Numerals 14 indicate cross-strands which extend diagonally between and connect the section 5 with section 6, said strands 14 at their intersecting parts, being connected by a thong 15 or equivalent means at the middle of a fascine, which operates to prevent sagging of parts or change in the form of a fascine.

In order that the water will be deflected to advantage for the rapid formation of silt beds, strands 16 are employed for connecting the strips, said strands 16 being secured to the strips near the ends thereof, and it 50 will be seen that, by use of the strands 16, the adjacent ends of strips 8 of section 5 are connected with the adjacent ends of strips 11 of section 6, these connections being near, but somewhat inwardly from the ends of 55 said strips; also the ends of the strips 7 which are adjacent to each other, are connected by strands 16; also it will be noted that, by use of strands 16, the ends of the strips of sections 5, which are disposed at 60 right angles to each other, are connected with each other and also with the ends of the strips 7.

On account of the construction described, the fascines, in side elevation and plan, present the same appearance, the result being that their operation for deflecting a water current to form silt beds will be the same when supported upon either end or upon either side, and since the ends of the strips 75 project somewhat beyond their connections with the strands 16, these end-portions will engage the ground at the bottom of a stream to advantage to prevent skidding or displacements.

In the use of the herein described silt accumulating means, the fascines are connected with each other, approximately at their middle, and by use of a stationary cable, may be maintained in a moving current parallel therewith and near the shore, as shown in Fig. 3, the result being that silt 105 will be deposited and erosion of the bank of a stream may be prevented; and as shown in Fig. 4, the fascines when connected, may 110

be maintained transversely of a water current by stationary cables 4, to form silt-beds.

In some instances the strands 16 may be omitted, and also the strands 14 may be dispensed with in other instances, depending upon the more or less rapid movement of water; also a single fascine may be used or a plurality of connected fascines may be employed, according to requirements.

10 It will be understood that any suitable material may be used. Since the fascines should ordinarily be disposed upon the bottom of a stream, some of the material should be metal. However I do not wish to limit myself to material to be used, nor to form, size, proportion of parts nor minor details, except so far as defined in or determined by the appended claim.

I claim:

20 In silt accumulating means, a fascine including a pair of sections each consisting of parallel strips arranged in pairs, the pairs of strips of said sections being disposed in

engaged relation at right-angles with reference to each other, cross-strips engaging the strips of each section at their parts of intersection, thongs securing the cross-strips to the pairs of strips of each section at the intersecting parts thereof, connected cross-strands extending diagonally between and connected with the strips of the sections and also connected with the cross-strips, and strands outwardly of the intersecting parts of said strips, said last named strands connecting the ends of the cross-strips with each other and connecting strips of the pair of sections and also connecting the ends of the strips of said sections with the ends of the cross-strips.

In testimony whereof, I have affixed my signature in presence of two witnesses.

HENRY F. KELLNER,

Witnesses:
